UNITED STATES PATENT OFFICE

CHARLES R. BROOKS, OF CHICAGO, ILLINOIS, ASSIGNOR TO RESERVE HOLDING COMPANY, OF CHICAGO, ILLINOIS, A CORPORATION OF DELAWARE

RELAY CONTROL CIRCUIT

Application filed September 26, 1929. Serial No. 385,249.

The present invention relates in general to relay control circuits, but more particularly with the control of the functioning of a relay when connected up in a circuit which includes a dry disc rectifier or electronic valve such as are now in general use. In order to illustrate the invention the same is incorporated in a well-known type of selector switch used in extending connections 10 from a calling line of an automatic telephone system in the direction of a called line.

To those familiar with automatic telephone practice, it is well known that the controlling armature of the line relay of an automatic switch, having the conventional circuits, closes the circuit of the associated release relay when the line relay is energized and closes a circuit for the operating 20 magnet and the associated changeover relay when the line relay deenergizes. In such circuits, the operating circuit is not closed until the armature spring of the line relay comes into engagement with its resting contact, and the circuit of the release relay is not closed until the said armature spring of the line relay comes into engagement with its working contact. Consequently, the 25 time which elapses while the armature spring is in its mid-position is sufficient to allow the release relay and the changeover relay to drop back unless some means are provided to render them slow to release. In the past this result has been accomplished 30 in various ways, i. e., by placing a slug on the core of the relay, or by placing a high resistance in multiple with the relay.

While these methods have proved satisfactory to a certain degree, they tend to make the relay somewhat sluggish on both the pull up and release operations. It is applicant's object to provide an improved arrangement for accomplishing the desired 40 result by suitably revising the circuits so that the shunt path around the relay is very high to current supplied to the relay from an exterior source, while this high resistance path becomes a low resistance path to induce current as soon as the line relay 45 opens its energizing circuit, so that the max-

imum amount of induced current generated is free to flow through the relay to hold it operated while the armature of the line relay alternately interrupts its energizing circuit.

In an exchange using a number of such 55 selectors, it is customary to provide supervisory alarm equipment which functions to inform an attendant if any switch or switches fail to properly release. To accomplish this it is customary to place a low-resistance slow-to-energize relay in series 60 with the operating circuits of the release magnets of each of a group of such selector switches. This slow-to-energize relay closes 65 an alarm circuit if any release circuit is closed a longer time than is ordinarily required to release a switch.

In accordance with the present invention 70 an ordinary relay is provided in a circuit including a rectifying unit, which functions in a manner to make the relay slow to pull up.

The single sheet of drawing shows by 75 means of the usual circuit diagram, a sufficient amount of apparatus used in an automatic telephone system to enable the invention to be readily understood.

The substation A is of the usual automatic type, having the usual talking and 80 signalling instrumentalities, and a switch controlling calling device CD.

The lineswitch LS may be of the well-known rotary type in which the wipers have no normal position and move in a forward 85 direction only.

The selector D is of the well-known vertical and rotary type, having 100 sets of bank contacts arranged in ten horizontal 90 rows or levels.

The control circuits of the selector D have been revised so as to embody the principles of the invention.

In order to explain the operation of the improved circuits, it will be assumed that a 95 subscriber at substation A desires to converse with some other subscriber of the system. When the receiver is removed at substation A the lineswitch LS functions in a well-known manner to extend the connec- 100

- tion to the selector D. The circuit to the selector extends from the negative terminal of battery supplied to the upper winding of the line relay 35, the armature 52 and its 5 resting contact, conductor 24, wiper 21, through the substation apparatus at A, wiper 23, conductor 26, resting contact and armature 55, to the lower winding of the line relay 35 and ground.
- 10 The line relay 35, upon energizing, closes a circuit at armature 46 for the release relay 36. This circuit extends from the grounded resting contact and armature 54, armature 46 and its working contact, 15 through the winding of relay 36, to battery and ground. The electronic valve 15, connected in multiple with relay 36 is so poled with respect to the battery that it prevents the flow of any appreciable current directly 20 supplied by the battery from passing around the relay 36. The relay 36, upon energizing, at armature 48 opens a point in the circuit of the release magnet 41 and prepares a circuit for the vertical magnet 40, and at armature 47 places ground on the release trunk conductor 25, thereby closing the usual holding circuit for the lineswitch LS.
- 25 The calling subscriber now operates the calling device CD in accordance with the 30 first digit of the desired number, whereupon the circuit of line relay 35 is opened a corresponding number of times at the calling substation. Each time line relay 35 de-energizes in response to one of the inter- 35 ruptions produced in its circuit, it opens the initial circuit of release relay 36 and closes the following series circuit for the change-over relay 37 and vertical magnet 40; from ground at the resting contact and armature 40, armature 46 and its resting contact, armature 48 and its working contact, through the changeover relay 37, and winding of vertical magnet 40, to battery. The 45 electronic valve, in multiple with 37, is so poled with respect to the battery that it prevents any appreciable current flow from the battery around the relay 37. The resistance of relay 37 is comparatively low and consequently the vertical magnet is energized 50 upon each deenergization of the line relay 35 to elevate the wipers of the switch D to the desired level of bank contacts in the usual manner. Each time the line relay 35 restores its armature it opens the traced circuit for relay 36, but the relay 36 does not deenergize because the decrease in electromagnetic saturation of the relay core which occurs when its energizing circuit is opened causes an E. M. F. to be induced in its own 55 winding in the same direction as that formerly supplied by the battery. This induced E. M. F. follows the low resistance path provided by the valve 15 which tends to delay the release action of the relay by prolonging the magnetic field of the relay coil. 60
- 65

When the armature 46 is again attracted the vertical magnet 40 deenergizes, but the relay 37, having a circuit arrangement similar to that of relay 36, functions in the same manner as the latter relay and, therefore, 70 does not restore its armature until an elapse of appreciable delay jointly determined by the valve and the characteristic of the relay windings.

Upon the energization of the changeover 75 relay 37, in response to the first impulse of current sent to the vertical magnet 40, as pointed out above, a circuit is closed for the stepping relay 38 at its armature and working contact. This circuit extends from the grounded contact and armature 47, through the front contact and armature of relay 37, off-normal contacts 44, the interrupter springs of rotary magnet 42, and through the winding of 38 to battery. The stepping relay 38, upon energizing, closes a locking circuit for itself at its armature 50, and at its armature 51 prepares a circuit for the rotary magnet 42.

At the end of the vertical movement, armature 46 comes to rest in an energized position, and series relay 37, being open-circuited for a prolonged interval eventually deenergizes, and at its armature opens the initial circuit of the stepping relay 38 and completes the circuit for the rotary magnet 42. The rotary magnet 42, upon energizing, advances the wipers 56—58, inclusive, into engagement with their first set of contacts in the level opposite which they were raised and at the end of its stroke opens the circuit of the stepping relay 38, at its interrupter contacts. Relay 38, upon deenergizing, opens the circuit of the rotary magnet 42 at armature 51, whereupon the rotary magnet 42 deenergizes and again closes its interrupter contacts. The alternate operation of stepping relay 38 and rotary magnet 42 continues in the usual manner until an idle or ungrounded trunk is reached, whereupon the switching relay 39 which was heretofore short circuited now energizes in series with the stepping relay 38 over the following circuit: from ground by way of the working contact and armature 47, switching relay 39, off-normal contacts 44, the interrupter contacts, and the stepping magnet 38 to battery. The stepping relay 38, however, does not energize at this time on account of the high resistance of the switching relay. The switching relay, however, operates and at its armatures 52 and 55 breaks away from its resting contacts and extends the connection to the line relay of the switch ahead, thereby disconnecting the line relay 35. When the line relay 35 is disconnected, armature 46 falls back and again opens the circuit of relay 36, but owing to the slow-release characteristics of this relay it does not deenergize until sufficient time has 90

elapsed to permit ground potential, supplied over to conductor 65 from the switch ahead, to replace that formerly supplied to the working contact and armature 47.

5 The switch seized by the selector D may be a second selector similar to the switch D or a connector switch for completing the connection to the called line. Since, however, the present invention is not concerned 10 with the type of switches used, it will be sufficient to assume that the subscriber at substation A decides to abandon the call and, therefore, replaces his receiver.

When the receiver is replaced at the 15 station A the switch seized by the selector D removes ground potential from conductor 65, thereby bringing about the release of the lineswitch LS and the selector D. These switches are both released in the usual and 20 well-known manner.

Attention, however, is called to the release circuit of switch D, which includes a release alarm relay 56, having its action modified by the presence of an electronic 25 valve 17. When ground potential is removed from conductor 65 the switching relay 39 deenergizes and at its armature 54 and its grounded contact completes the circuit for the release magnet. This circuit 30 extends by way of armature 46 and its resting contact, armature 48 and its resting contact, the off-normal springs 43, the winding of the release magnet 41, and the winding of the release alarm relay 56 and the electronic valve 17 in multiple, to battery. If 35 the switch releases as it should, the off-normal springs 43 will open the circuit of release magnet 41 and of the alarm relay 56 before sufficient time has elapsed to cause 40 the alarm relay to operate. This delay in operation of the alarm relay is caused by the action of the valve absorbing a charge which impedes the path of the impressed E. M. F. in direct ratio to the ohmic resistance of the valve in its low resistance 45 direction. This condition persists until the valve receives its maximum charge, at which time the surplus E. M. F. passes to the relay winding to operate it. The relay is quick 50 to restore, however, because the valve acts as a high resistance shunt to current induced in the winding of the release alarm relay 56 when the latter relay circuit is broken.

What is claimed is:

- 55 1. In an operating circuit for a single coil relay having an armature, a source of direct current energy and a circuit closing device, and an electronic valve also in circuit with said relay coil for maintaining said armature in operated or released position when said circuit is intermittently closed for a prolonged period, depending on the polarity of said valve with respect to said current.
- 60 2. In an impulsive circuit, a relay, a pair

of conductors extending from said relay, a battery, one of said conductors extending to one terminal of said battery, a pair of contacts for intermittently supplying current by way of the other conductor from said battery to the other terminal of said relay to operate the same, and an electronic valve in bridge of said conductors preventing the deenergization of said relay while said contacts are momentarily opened irrespective of the 70 number of times said contacts are opened so long as any period of opening does not exceed the maximum first period which they could have been opened without changing the position of the relay.

3. In combination with a single coil relay, a circuit through the relay coil including a source of operating energy, means for intermittently closing said circuit, and means for modifying the influence of the intermittently closed circuit on said relay comprising an electronic valve connected across the terminals of said coil.

4. In a relay control arrangement, a relay, an operating circuit for said relay comprising a source of current and a device for producing series of interruptions in said circuit, and auxiliary means permanently connected across the terminals of said relay having a high resistance to the current flow 90 in its operating circuit and a low resistance to current induced in said relay flowing when the operating circuit is interrupted for holding said relay operated during such period.

5. In combination with a single coil relay, an operating circuit therefor including a supply of direct current operating energy, an electronic valve having an infinite resistance to current flow in one direction and an extremely low resistance to current flow in the reverse direction, means for connecting said valve across the terminals of said relay to make the same slow to pull up while its former characteristic as regards to its falling away is retained or slow to fall away with like retention of its characteristic as regards its pulling up action depending on the polarity of said valve with respect to said source of energy.

In witness whereof, I hereunto subscribe my name this 23rd day of September, A. D. 1929.

CHARLES R. BROOKS.
